US00D856414S

(12) **United States Design Patent** (10) Patent No.: **US D856,414 S**
 Jameson et al. (45) Date of Patent: **** Aug. 13, 2019**

(54) **LABEL SHEET ASSEMBLY WITH FEED EDGE DRESS**

(71) Applicant: **CCL LABEL, INC.**, Framingham, MA (US)

(72) Inventors: **Alan Jameson**, West Covina, CA (US); **Eric Cushing**, Riverside, CA (US); **Le-Hoa Hong**, Brea, CA (US); **Sriram Venkatasanthanam**, Chino Hills, CA (US); **Adam Bratter**, Newport Coast, CA (US); **Heba Armand**, Placentia, CA (US); **Ana Trinh**, Rowland Heights, CA (US)

(73) Assignee: **CCL LABEL, INC.**, Framingham, MA (US)

(**) Term: **15 Years**

(21) Appl. No.: **29/638,873**

(22) Filed: **Mar. 1, 2018**

(51) LOC (12) Cl. **19-01**

(52) U.S. Cl.

USPC **D19/1**

(58) **Field of Classification Search**

(57) **CLAIM**

The ornamental design for a label sheet assembly with feed edge dress, as shown and described.

DESCRIPTION

FIG. 1 is a perspective view of a first embodiment of our new design;

FIG. 2 is a front side view thereof;

FIG. 3 is a rear side view thereof;

FIG. 4 is a first side view thereof;

FIG. 5 is a second side view thereof;

FIG. 6 is a top side view thereof;

FIG. 7 is a bottom side view thereof;

FIG. 8 is a perspective view of a second embodiment of our new design;

FIG. 9 is a front side view thereof;

FIG. 10 is a rear side view thereof;

FIG. 11 is a first side view thereof;

FIG. 12 is a second side view thereof;

FIG. 13 is a top side view thereof;

FIG. 14 is a bottom side view thereof;

FIG. 15 is a perspective view of a third embodiment of our new design;

FIG. 16 is a front side view thereof;

FIG. 17 is a rear side view thereof;

FIG. 18 is a first side view thereof;

FIG. 19 is a second side view thereof;

FIG. 20 is a top side view thereof;

FIG. 21 is a bottom side view thereof;

FIG. 22 is a perspective view of a fourth embodiment of our new design;
FIG. 23 is a front side view thereof;
FIG. 24 is a rear side view thereof;
FIG. 25 is a first side view thereof;
FIG. 26 is a second side view thereof;
FIG. 27 is a top side view thereof;
FIG. 28 is a bottom side view thereof;
FIG. 29 is a perspective view of a fifth embodiment of our new design;
FIG. 30 is a front side view thereof;
FIG. 31 is a rear side view thereof;
FIG. 32 is a first side view thereof;
FIG. 33 is a second side view thereof;
FIG. 34 is a top side view thereof;
FIG. 35 is a bottom side view thereof;
FIG. 36 is a perspective view of a sixth embodiment of our new design;
FIG. 37 is a front side view thereof;
FIG. 38 is a rear side view thereof;
FIG. 39 is a first side view thereof;
FIG. 40 is a second side view thereof;
FIG. 41 is a top side view thereof;
FIG. 42 is a bottom side view thereof;
FIG. 43 is a perspective view of a seventh embodiment of our new design;
FIG. 44 is a front side view thereof;
FIG. 45 is a rear side view thereof;
FIG. 46 is a first side view thereof;
FIG. 47 is a second side view thereof;

FIG. 48 is a top side view thereof;
FIG. 49 is a bottom side view thereof;
FIG. 50 is a perspective view of an eighth embodiment of our new design;
FIG. 51 is a front side view thereof;
FIG. 52 is a rear side view thereof;
FIG. 53 is a first side view thereof;
FIG. 54 is a second side view thereof;
FIG. 55 is a top side view thereof;
FIG. 56 is a bottom side view thereof;
FIG. 57 is a perspective view of a ninth embodiment of our new design;
FIG. 58 is a front side view thereof;
FIG. 59 is a rear side view thereof;
FIG. 60 is a first side view thereof;
FIG. 61 is a second side view thereof;
FIG. 62 is a top side view thereof;
FIG. 63 is a bottom side view thereof;
FIG. 64 is a perspective view of a tenth embodiment of our new design;
FIG. 65 is a front side view thereof;
FIG. 66 is a rear side view thereof;
FIG. 67 is a first side view thereof;
FIG. 68 is a second side view thereof;
FIG. 69 is a top side view thereof; and,
FIG. 70 is a bottom side view thereof.

The broken lines in the figures are included for the purpose of illustrating portions of a label sheet assembly with feed edge dress and form no part of the claimed design.
